DESIGN FOR A DISPENSER FOR LIQUIDS, OR SIMILAR ARTICLE

Thomas D'Addario, Astoria, N. Y., assignor to
Starman Syphon Manufacturing Co., Inc.,
Brooklyn, N. Y.

Application November 27, 1939, Serial No. 88,506

Term of patent 3½ years

To all whom it may concern:

Be it known that I, Thomas D'Addario, a citizen of the United States, residing at Astoria, in the county of Queens and State of New York, have invented a new, original, and ornamental Design for a Dispenser for Liquids, or Similar Article, of which the following is a specification, reference being had to the accompanying drawing, forming part thereof.

Fig. 1 is a side elevational view of a dispenser for liquids, or similar article, showing my new design.

Fig. 2 is an enlarged sectional view taken on line 2—2 of Fig. 1.

Fig. 3 is an enlarged sectional view taken on line 3—3 of Fig. 1.

Fig. 4 is a sectional view taken on line 4—4 of Fig. 1, as viewed in the direction of the arrows.

I claim:

The ornamental design for a dispenser for liquids, or similar article, substantially as shown.

THOMAS D'ADDARIO.
